H. B. SMITH

SEMILOOSE WRAPPED BOX

Filed Dec. 20, 1920

Inventor
Harry B. Smith,
By his Attorneys
Meyers, Cavanaugh Hyde

UNITED STATES PATENT OFFICE.

HARRY BRIDGMAN SMITH, OF BROOKLYN, NEW YORK.

SEMILOOSE-WRAPPED BOX.

Application filed December 20, 1920. Serial No. 431,912.

To all whom it may concern:

Be it known that I, HARRY BRIDGMAN SMITH, a citizen of the United States, and resident of Brooklyn, in the county of Kings

and State of New York, have invented certain new and useful Improvements in Semi-loose-Wrapped Boxes, of which the following is a specification.

My invention relates to a distinctly new type of box which may be called, for descriptive purposes, a "semi-loose wrapped" box.

Wrapped or covered paper boxes have heretofore been produced in two distinct types, in one of which, usually called in the trade a "tight-wrapped" box, the covering paper is adhesively secured to the shell material throughout their engaging areas. In the other type, known as a "loose-wrapped" box, the covering paper is adhesively connected to the shell only along relatively narrow, inturned marginal portions of the cover material, the exposed portions of the cover being unconnected to the shell, and lying more or less loosely thereon, and presenting a distinctly different appearance from the tight-wrapped boxes with their tightly fitting coverings.

An object of the present invention is to produce a new, distinctive and attractive style of box which has some of the characteristics of each of the well-known types, and which appeals to the trade by reason of its novelty of structure and appearance, strength and other structural characteristics, cheapness, and other considerations.

Another object is to provide a box which may be made by improved methods, with increased output-speed and economy.

Generally described, a box constructed in accordance with my invention comprises a shell, mainly connected to a cover sheet by adhesive contact throughout substantially the entire engaging areas of end portions of the respective parts, and with other portions of the shell and cover material substantially unconnected by adhesive, or connected only along narrow marginal portions of the respective blanks. A box so constructed has the cover paper tightly secured to the shell throughout the exposed end sur-

faces of the box, and loosely overlying the shell at all other exposed surfaces including the body portion (top or bottom of the box part, as the case may be) and sides.

55

While a box so constructed requires more adhesive than a box of complete loose-wrapped construction, it requires considerably less than a tight-wrapped box, and therefore, a considerable saving in cost of glue is accomplished as compared with boxes of the last-named type, while some of the characteristics of the tight-wrapped box are retained, and also some characteristics of the loose-wrapped type are incorporated, as previously explained.

Boxes of the present sort are well adapted for production by methods of my invention, in which a sheet or blank of shell material is applied to a sheet or blank of covering material with adhesive between them to form an initial assembly, and outwardly extending marginal portions of the cover blank or sheet are then folded over upon and adhesively secured to adjacent margins of the shell, these margins usually being outward portions of the side wings of the respective sheets or blanks, and the initial covered assembly is then bent or folded into complete box form. Such methods are shown in my previous applications Ser. No. 254,630, filed September 18, 1918 and Ser. No. 370,180, filed March 31, 1920.

In a companion application, executed on even date herewith, I have disclosed a method which is, in some respects, a continuation and improvement upon my previous methods as disclosed in the above mentioned applications, and is particularly suitable for making boxes of the present type.

The characteristics and advantages of my invention are further sufficiently explained in connection with a detail description of the accompanying drawing, which shows an exemplifying structure in which the invention is embodied. After considering this embodiment, persons skilled in the art will understand that many modifications may be made within the principles of the invention; and I contemplate the employment of any structures which are properly within the scope of the appended claims.

Fig. 1 is a bottom view of a suitable box shell blank, properly glued.

Fig. 2 is a top view of the same blank properly supplied with adhesive and placed upon a suitable cover blank.

Fig. 3 is a perspective view sufficiently explaining the manner in which the assembly of Fig. 2 may be shaped into box form.

Fig. 4 is a perspective view of a completed box part, either the "top" or "bottom" section of a two-part box, embodying my invention.

Fig. 5 is a horizontal section in the plane 5—5, Fig. 4.

15 Fig. 6 is a vertical section on the line 6-6, Fig. 4.

Fig. 7 is a transverse section on the line 7-7, Fig. 4.

Fig. 1 shows a shell blank S, usually of
20 card-board of suitable thickness, comprising
a body portion 1, side wings 2, end wings 3
and corner laps 4, in this case extending
from the ends of the side wings. The blank
is severed on the lines 5 to disconnect adjac-
25 ent portions of the end wings and corner
laps, and is scored or creased along the lines
6 to facilitate subsequent bending. On the
under surface of the blank as shown in Fig.
1, adhesive is applied to the surfaces of the
30 end wings, and corner laps; and although
it is not necessary in all cases to entirely
cover these portions of the blank, it is prefer-
erable in some cases to entirely cover these
surfaces with adhesive, as in the present ex-
35 amplification of the invention. Other por-
tions of this surface of the blank, namely
the body portion 1 and side wings 2, are
preferably left entirely free of adhesive,
as shown.

40 Stripes 7 of adhesive are placed along outer margins of the upper surfaces of side wings and adjacent ends of the corner laps, as shown in Fig. 2, and also along upper surface margins 8 of the end wings, and the
45 shell blank is placed flatwise upon a co-operative cover blank C, as shown in Fig. 2, this blank comprising a body portion 10, side wings 11, end wings 12 and corner laps 13, which may desirably be cut away on the
50 diagonal lines 14, although this is not essen-

55 The cover blank also has the side wings formed with projecting margins 15 and the cover end wings have projecting margins 16. The cover side wing margins 15 are now folded over and pressed upon the adhesive stripes 7 of the shell surfaces (one of the cover margins being shown folded over and the other un-folded in Fig. 2).

folded in Fig. 2) producing a complete box blank assembly. This is now shaped into box form, involving in the present embodiment the steps of separating shell end wings 3 from cover end wings 12, as shown in Fig. 3, whereupon the previously engaged surfaces of these wings are exposed, both

covered with adhesive, the adhesive upon surfaces of the cover end wings having been placed thereon by previous contact with the shell end wings. The side wings of the assembly are then folded up as also shown in Fig. 3; the corner laps are folded in against the adhesive surfaces of the shell end wings 3; the cover end wings are then brought back toward the shell end wings, and their adhesive surfaces secured to outer surfaces of the corner laps, and when the adjacent ends of the corner laps do not approximately meet, parts of the inner surfaces of the cover end wings are engaged with central outer surface-portions of the shell end wing. The box blank is usually shaped over a former or plunger (not shown in the drawing) so that the parts may be suitably pressed and secured in position. The projecting margins 16 of the cover end wings are then turned in and down and secured upon adhesive stripes 8 of the shell end wings.

There is thus produced a box structure shown in Fig. 4, in which the exposed end portions, consisting of cover end wings 12, are tightly glued to underlying parts of the box-end structure, and all other exposed portions of the box, consisting of the cover side wings 11 and body portion 10, are entirely free from the underlying shell portions and lie more or less loosely thereon, this freedom being indicated by spaces in sectional Figs. 5, 6 and 7 between the shell and adjacent portions of the cover side wings and body portion, while the tight adhesive engagement of end portions of the structure is indicated in Figs. 5 and 6, by the absence of any space between the cover and shell members respectively. The end portions of the complete box, therefore, present the appearance of a tight-wrapped box and the central (side and body) portions present the appearance of a loose-wrapped box. The completed box part is also characterized by the absence of any exposed or raw edges of the shell material, since at every exposed point the shell material is completely enclosed by the cover paper.

The terms "side" and "end", as applied to different wing portions of the blanks and to parts of the completed box, have mainly relatively and not limiting significance, since evidently if the sides are made shorter and the ends are made longer, the present sides of the box will then appear to be ends, and vice versa. 120

After considering the single embodiment of the invention above described, and especially after also considering my other applications herein mentioned, persons skilled in the art will understand that many variations may be made within the principles of the invention; and I contemplate the em- 130

placement of any structures which are properly within the scope of the appended claims.

I claim:

1. A box consisting of a covered shell characterized by the exposed cover material being tightly secured on two opposite walls of the box and loosely applied on other walls of the box.
2. A box consisting of a covered shell, characterized by the cover material being tightly secured at the ends of the box and comparatively-loosely overlying the sides and body portion of the shell.
3. A semi-loose wrapped box comprising a shell and a cover sheet tightly secured to the ends of the shell and comparatively loosely overlying the shell at other exposed surfaces.
4. A box blank comprising a sheet of shell material and a sheet of cover material in flatwise contact, end portions of the blank being adhesively secured together and intermediate portions being free from each other.
5. A box blank comprising a sheet of shell material and a sheet of cover material in flatwise contact, end portions of the blank being adhesively secured together and intermediate portions be unconnected by adhesive.
6. A box blank consisting of assembled sheets of shell and cover material and comprising a body portion, side and end wings and corner laps, the shell and cover material composing the end wings and corner laps being tightly secured together by adhesive and remaining portions of the shell and cover material being substantially free of adhesive.
7. A box blank consisting of assembled sheets of shell and cover material and comprising a body portion, side and end wings and corner laps, the shell and cover material composing the end wings and corner laps being tightly secured together by adhesive and remaining portions of the cover material being unconnected to the shell and relatively loose thereon.
8. A box blank comprising a body portion, side and end wings and corner laps, and composed of a sheet of shell material and a sheet of cover material in facial contact, the contacting faces of the end wings and corner laps of the respective sheets being substantially completely secured together by adhesive, the other contacting faces of the respective sheets being substantially free and unconnected by adhesive.
9. A box blank comprising a body portion, side and end wings and corner laps, and composed of a sheet of shell material and a sheet of cover material in facial contact, the contacting faces of the end wings and corner laps of the respective sheets being substantially completely secured to-

gether by adhesive, the other contacting faces of the respective sheets being substantially free and connected by adhesive, the side marginal portions of the cover sheet being folded over and adhesively secured to upper marginal surfaces of the shell sheet.

10. A box blank assembly comprising a blank of shell material in flatwise contact with a blank of cover material, the cover and shell blank having approximately corresponding body portions, side and end wings and corner laps, the confronting surfaces of the end wings and corner laps of the respective blanks being substantially completely coated with adhesive and the remaining contacting surfaces of the respective blanks being substantially unconnected.

11. A box blank assembly comprising a blank of shell material in flatwise contact with a blank of cover material, the cover and shell blank having approximately corresponding body portions, side and end wings and corner laps, the confronting surfaces of the end wings and corner laps of the respective blanks being substantially completely coated with adhesive, and the remaining contacting surfaces of the respective blanks being substantially unconnected, marginal portions of the cover blank side wings being folded over upon and adhesively secured to upper marginal surfaces of the shell blank side wings.

12. A box structure comprising a body portion, sides and ends and consisting of a shell and a cover sheet enclosing outer surfaces of the shell, the cover sheet being adhesively secured to underlying parts of the end-structure and substantially free and relatively loose about the sides and body portion of the structure.

13. A box structure comprising a shell and an overlying cover and having ends, sides and a body portion, the ends including corner laps extending from the sides and enclosed by parts of the shell and cover, the parts of the end structure of the box being substantially tightly secured together by adhesive, and the parts of the sides and body portion being substantially free from each other.

14. A box structure comprising a shell and an overlying cover and having ends, sides and a body portion, the ends including corner laps extending from the sides and enclosed by parts of the shell and cover, the parts of the end structure of the box being substantially tightly secured together by adhesive, and the parts of the sides and body portion being substantially unconnected by adhesive.

15. A box consisting of a shell blank and a cover blank having co-operative body portions, side and end wings and corner laps, the corner laps of the respective blanks being adhesively secured together and inserted

between portions of the end wings of the respective blanks and adhesively secured, the side wings and body portion of the cover blank being substantially free from and relatively loose upon co-operative parts of the shell blank.

16. A covered box having a body portion, sides and ends, exposed parts of the cover

material being tightly secured at the ends of the box, and being relatively loose at the 10 sides and body portion.

Signed at New York, in the county of New York and State of New York this 17th day of December, A. D. 1920.

HARRY BRIDGMAN SMITH.
